Primary Examiner — Sandra Morris(74) *Attorney, Agent, or Firm* — Wood, Herron & Evans, LLP(57) **CLAIM**

The ornamental design for a lottery terminal, as shown and described.

DESCRIPTION

FIG. 1 is a perspective view of a lottery terminal with the broken lines adjacent to the shaded portions forming an unclaimed boundary of the design;

FIG. 2 is a front view of FIG. 1 of this invention;

FIG. 3 is a left side view of FIG. 1 of this invention;

FIG. 4 is a right side view of FIG. 1 of this invention;

FIG. 5 is a rear view of FIG. 1 of this invention;

FIG. 6 is a top view of FIG. 1 of this invention; and,

FIG. 7 is a bottom view of FIG. 1 of this invention.

Any elements shown in broken lines form no part of the claimed invention. The broken lines adjacent to the shaded portions form an unclaimed boundary of the design. The dash-dot lines are shown for environmental purposes only and form no part of the claimed design.
